CALCULATING MACHINE

Harold T. Avery, Oakland, Calif., assignor to
 Marchant Calculating Machine Company, a
 corporation of California

Application September 1, 1931, Serial No. 560,580

7 Claims. (Cl. 235—131)

The present invention relates to calculating machines and particularly to the type in which a selected number of increments may be transmitted to a numeral wheel at a high speed of 5 operation wherein suitable means are provided for positively limiting the movement of the numeral wheel to the selected number of increments and preventing overthrow thereof. The invention is disclosed as embodied in a machine of the 10 type shown in the patent to Friden No. 1,643,710, dated September 27, 1927, to which reference is hereby made for a disclosure of mechanisms not specifically described herein.

It is an object of the invention to provide an 15 improved mechanism for preventing overthrow of the numeral wheels upon movement thereof by any of a plurality of operating mechanisms.

Another object of the invention is to provide 20 means whereby the numeral wheels are released for free rotation during a digitation operation, and are positively locked at the end thereof to prevent overthrow.

Another object of the invention is the provision 25 of means for preventing overthrow of the numeral wheels, said means being controlled by the actuating mechanism.

Another object of the invention is the provision 30 of overthrow preventing means having a plurality of operating positions.

Another object of the invention is the provision 35 of overthrow preventing means which are positive in their operation and which reduce noise of the machine to a minimum.

Another object of the invention is the provision 40 of overthrow preventing means having a plurality of controlling means which are controlled by the actuating mechanism.

Another object of the invention is the provision 45 of overthrow preventing means permitting of a high speed of operation with a minimum of noise incident thereto.

Other objects will appear as the description progresses.

The present invention is shown as embodied in 50 a calculating machine of the type disclosed in the patent to Friden No. 1,643,710 dated September 27, 1927, and is an improvement on the structure shown in the patent to Friden No. 1,454,-275 dated May 8, 1923. The invention contemplates a locking of the numeral wheels at all 55 times when an operation involving movement of the same is not in progress, and a complete release of the numeral wheels during operation thereof, thereby permitting comparatively light spring pressure on the overthrow preventing

pawls so that the noise incident to the oscillation of said pawls is reduced to a minimum.

The overthrow preventing means disclosed in the present structure are provided with three distinct operating conditions. When no operation 5 of the numeral wheels is in progress said means are positively locked in engagement therewith, while during a digitation operation the overthrow preventing means are moved to inoperative position and the numeral wheels are free to rotate 10 without more than frictional resistance; during the portion of an operating cycle in which a transfer is made from one numeral wheel to the one of next higher order, it is necessary that the overthrow preventing means be resiliently held 15 into engagement with the numeral wheel, as said wheel must be free to receive a transfer in the event that such is determined, and must not be allowed to float out of position in the event that a transfer is not determined. This resilient engagement of the overthrow preventing means with the numeral wheel gear also maintains the alignment of the intermediate gear until the transfer tooth is engaged therewith, thus preventing a jamming of the machine. 20

In the accompanying drawing forming a part 25 of this specification:

Figure 1 is a right section through the actuator and the shiftable accumulating mechanism carriage, showing the parts as they are related 30 in normal position. The section of the actuator as shown in Figure 1 is taken along the line 1—1 in Figure 3, the transfer keys being dotted in to show their relative position with respect to the remainder of the actuating unit. 35

Figure 2 is a left elevation of an actuating unit of the calculating machine, showing the means for releasing the overthrow preventing means during digitation and for providing a resilient retaining means for said numeral wheels during 40 transfer operations.

Figure 3 is a rear elevation of one of the actuating units of the machine.

Figure 4 is a right elevation of one of the actuating units of the calculating machine. 45

Figure 5 is a detail view showing the means for releasing the overthrow preventing means during resetting operations.

As disclosed in the present embodiment, the invention is shown as applied to a calculating 50 machine having a rotary actuator 300 which may be operated by any suitable means. Values are introduced into the machine by suitable mechanism which moves the lever arm 301 through an angle corresponding to the desired value, said 55

arm being provided with an arcuate rack at the upper end thereof meshing with and adapted to move a settable disk 302 as fully disclosed in the Friden Patent No. 1,643,710. A box cam is formed in said disk to receive a roller 303A (Figure 1) attached to a slide 303 to control the time of projection thereof during a rotation of the actuator. The slide 303 is provided with nine teeth which are adapted to mesh with and actuate the intermediate gears 402 to register on the numeral wheel 401 the number represented by the setting of the disk 302, as disclosed in the above-mentioned patent. A locking pawl 404 is provided to lock the disk 302 in adjusted position during rotation of the actuator, the control thereof being provided through any suitable means.

Suitable means are provided for carrying tens from order to order, as fully disclosed in the above-mentioned patent. The only element thereof shown in the instant drawing is the transfer key 322 mounted in the actuator, said key being adapted to be rocked laterally against the tension of spring 322A by a transfer lever (not shown) to engage the intermediate gear 402 and transmit one increment of movement to a higher order wheel when the wheel of next lower order passes from 0 to 9, or 9 to 0. The means for restoring any tripped transfer levers are also shown in the accompanying drawing, said means comprising the restoring cam 323 (Figures 3 and 4).

Any suitable means for resetting the numeral wheels 401 to zero may be provided, the only portion of such resetting means shown herein being the means for releasing the overthrow preventing pawls during resetting operation, comprising a cam mounted on the resetting shaft which is rotated by suitable operating means.

The numeral wheels 401 are rotatably mounted on a shaft 410 which is journaled in a shiftable carriage placed in parallel displaceable relation with respect to the actuating mechanism. Secured to the side of each numeral wheel 401 is a numeral wheel gear 403 having ten teeth. Normally engaging said numeral wheel gear is a pawl 404 which is thrust into engagement therewith by a spring 405 tensioned between the tail of said pawl and a suitable supporting member in the accumulating carriage. While the numeral wheels are shown as being mounted in a shiftable carriage, the invention as disclosed is equally applicable to a machine in which the actuator is displaceable with respect to the accumulator, or the two are relatively stationary.

Means are provided for normally holding the pawl 404 in locking engagement with the numeral wheel 401. A bellcrank lever 420 is loosely mounted on a shaft 421, being normally held in the position shown in Figure 1 by a compression spring 420A suitably tensioned between the upper arm of said bellcrank and a plate 422. The lower and forwardly extending arm of the bellcrank lever 420 is held in lateral alignment by a downwardly projecting comb extension of plate 422, and is provided at the end with a nose 420B having a double camming surface, the upper surface of which is adapted to block movement of the pawl 404 by engagement with a lateral extension 404A provided thereon. The pawls 404 are normally spring pressed into fully seated position, and the nose 420B of the bellcrank lever 420 serves not to hold the pawl in its fully seated position, but merely to lock the pawl safely below the line of the tips of gears 403, thereby effectu-

ally locking the accumulating wheel 401 in any given position.

Means are provided for completely releasing the numeral wheels from the overthrow preventing pawl during digitation. Secured to the actuating slide 303 and to one side of the operating teeth thereof is a cam 303B which is adapted, upon rotation of the actuator, to contact the rearward and upwardly extending arm 420C of the bell-crunk lever 420 to rock said lever in a counter-clockwise direction to its extreme position in that direction. The arm 420C is held in the proper position by a suitable comb formed integrally with plate 422. The lower camming surface of nose 420B on the lower arm of the bell-crunk lever 420 is adapted to contact a pin 404B on the pawl 404, and rock said pawl in a clockwise direction to release the numeral wheel 401 therefrom. The release of the numeral wheel 401 from the pawl 404 is effected only during digitation as the cam 303B becomes effective and ineffective in time with the teeth of the actuating slide 303 so that the release is effected immediately prior to the engagement of the slide with the intermediate gear 402, and the pawls 404 are released immediately upon retraction of said slide, or when the slide passes operative position. At either of these times the spring 405 becomes effective to reseat the pawl 404 in engagement with the gear 403, and the bellcrank lever 420 under influence of spring 420A again moves into blocking position behind the lug 404A on the pawl 404. Thus it is seen that the numeral wheels are released for free rotation during digitation and immediately thereafter are stopped at the selected registration, further movement thereof being blocked.

Means are provided for releasing the locking means for the numeral wheels during a carrying operation, the overthrow preventing means remaining in spring pressed engagement therewith. Integrally formed on a supporting disk of an actuator unit 300 is a cam surface 322B laterally aligned with the respective transfer pins 322. Said cams are so positioned as to become effective immediately after the cam 303B to rock the bellcrank 420 in a counter-clockwise direction. The movement imparted to the bellcrank lever 420 by the cam 322B is less than the movement imparted thereto by the cam 303B so that the lower and forward arm 420B thereof is rocked downwardly to permit the pawl 404 to be oscillated by the gear 403, but not to such an extent that the nose 420B will rock the pawl 404 by contacting the pin 404B. This intermediate position of the bellcrank lever 420 allows the pawl 404 to remain in engagement with the gears 403 and act as a normally spring pressed overthrow preventing pawl. This ensures the alignment of gears 403 and 402 so that the transfer pin 322 can mesh therewith and prevents the numeral wheel 401 from floating out of position in the event that no transfer is determined in that order.

From the foregoing description it appears that the bellcrank lever 420 is adapted to occupy three different positions to determine three different operating conditions of the overthrow preventing pawl 404. In the normal position shown in Figure 1, the forward arm 420B of said bellcrank lever lies in front of the lug 404A on the pawl 404, preventing a complete release of the pawl 404 from the numeral wheel gear 403, positively locking the numeral wheel 401 in position.

In the intermediate position of the bellcrank lever 420, to which position it is moved by either of the cams 322B during the transferring portion of the cycle of operation, the forward nose 420B of said bellcrank lever is moved downwardly out of blocking relation with the lug 404A, but not so far as to release the pawl 404 from the numeral wheel, thus allowing it to operate as a normal spring pressed pawl during such operation. In the extreme rocked position of the bellcrank lever 420 in a counter-clockwise direction, as imparted thereto by the cam 303B during digitation operation, the forward nose 420B of the bellcrank lever engages the pin 404B secured to the pawl 404 and rocks said pawl completely out of engagement from the intermediate numeral wheel gear 403, thus permitting free rotation of the numeral wheel during digitation operations.

Means are provided for releasing the numeral wheels for free rotation during a resetting operation. Secured to the resetting shaft 410 is a cam disk 413 having a depression which is adapted to receive the nose of a member 414 mounted on the shaft 406 (Figure 5) when the resetting shaft 25 is in normal or full cycle position. Said member 414 is held in spring pressed engagement with the cam disk 413 by a spring 415 suitably supported on an arm 415A as shown in Figure 5. Upon rotation of the resetting shaft 410, the cam disk 413 forces the projection on member 414 from engagement with the seat in said cam disk, and rocks the shaft 406 in a counter-clockwise direction. As shown in Figure 1, counter-clockwise rotation of shaft 406 depresses the forward arm of the bellcrank 420, causing the nose 420B formed thereon to contact pin 404B to release the pawl 404 from engagement with the numeral wheel gears 403, releasing the numeral wheel for free rotation as in digitation operations.

While the preferred construction has been described in the foregoing specification, it is understood that the invention is capable of modification within the scope of the following claims.

I claim:

1. In a calculating machine, numeral wheels, spring pressed detents associated therewith, a member for preventing movement of said detents to inoperative position, and means comprising said member for moving said detents to inoperative position.

2. In a calculating machine, numeral wheels, overthrow preventing means therefor, means normally holding said overthrow preventing means to lock said numeral wheels against movement in either direction, actuating mechanism for

said numeral wheels, selecting mechanism therefor including a differentially settable element, and means controlled by said element for disabling said holding means during effective movement of said actuating mechanism.

3. In a calculating machine, numeral wheels, overthrow preventing means therefor, means normally holding said overthrow preventing means to lock said numeral wheels against movement in either direction, actuating mechanism for said numeral wheels, selecting mechanism therefor including a differentially settable element, and means controlled by said element for disabling said holding means and moving said overthrow preventing means from engagement with said numeral wheels during effective movement of said actuating mechanism.

4. In a calculating machine, a toothed registering wheel, a spring-pressed detent in cooperative relation therewith, a lever for blocking movement of said detent in either direction by said wheel, means for moving said lever to free said detent for movement in either direction by said wheel, and means comprising said lever for completely removing said detent from cooperative relation with said wheel.

5. In a calculating machine, a toothed registering wheel, a spring-pressed detent in cooperative relation therewith, means for locking said wheel against movement comprising means for blocking movement of said detent, a digitation member having means associated therewith for completely removing said detent from cooperative relation with said wheel, and a tens carrying member having means associated therewith for disabling said blocking means only.

6. In a calculating machine, a numeral wheel, a spring pressed detent associated therewith, a lever for controlling movement of said detent, actuating mechanism comprising a digitation member and a tens carrying member, and means associated with each of said members for causing different movements of said lever in carrying than in digitation operations.

7. In a calculating machine, a registering wheel, a spring pressed detent associated therewith, a control lever movable to a series of positions to block movement of said detent, to permit said detent to be moved by said wheel, or to remove said detent from operative association with said wheel, reversible actuating mechanism, and means controlled by said mechanism for causing movement of said lever to each of said positions during operation in either direction.

HAROLD T. AVERY. 55
